UNITED STATES PATENT OFFICE.

GEORGE HOOKHAM, OF BIRMINGHAM, ENGLAND.

BOTTLE-STOPPER.

No. 868,784.

Specification of Letters Patent.

Patented Oct. 22, 1907.

Application filed March 7, 1906. Serial No. 304,756.

To all whom it may concern:

Be it known that I, GEORGE HOOKHAM, a subject of the King of Great Britain and Ireland, residing at 7 and 8 New Bartholomew street, Birmingham, in the county 5 of Warwick, England, manufacturer, have invented new and useful Improvements in Bottle-Stoppers, of which the following is a specification.

The invention relates to bottle stoppers and has for its object to effect improvements in that kind of bottle 10 stopper which is described in my Patent No. 787669 patented April 18, 1905, these improvements being specially directed towards the attainment of great compressibility and cheapness of construction of the bottle stopper.

15 The invention consists in forming a bottle stopper with a body part of wood which has been treated mechanically so as to break up the hard cellular structure of the wood and thereby render it very compressible. This body part may be used by itself and treated with 20 paraffin wax, pitch or the like, or in addition it may be provided with a central hole, or grooves or with both and covered or partially covered with capsules or a capsule.

Referring now to the accompanying drawings which 25 illustrate the application of this invention in various ways, Figure 1 shows the invention in its simplest form. Fig. 2 shows a modification having a central hole. Fig. 3 shows an additional modification in which a plug has been inserted in the central hole. Figs. 4 and 5 are end 30 views showing two arrangements of grooves which may be employed for the purpose of giving greater compressibility. Fig. 6 is an outside view of a bottle stopper according to the present invention, completely covered by a capsule. Fig. 7 shows another form of grooving, and Fig. 8 shows a stopper with a capsule and internal grooves.

In carrying the invention into effect according to one form, a solid wooden cylinder or prism is compressed in any suitable manner so as to break up the hard cellular 40 structure which binds the fibers of the wood. This is preferably effected by squeezing the wood through a suitable die which in the case of American white wood has about one half the sectional area of the uncom- 45 pressed cylinder or prism. When this is done suitable lengths may be cut from the wood so compressed so as to give a convenient length of stopper, *a*, as shown in Fig. 1. When this cork is soaked in water it assumes its original size and shape after which it is dried. By 50 this means some woods, as for instance, American white wood, are rendered so compressible that stoppers so treated may for some purposes be used without further treatment except impregnating the upper portion with any suitable waterproofing material such as paraffin wax or pitch.

55 In order to give additional compressibility, however,

it is generally preferred to drill a hole, *b*, (Fig. 2) up the center of the body, *a*, for about three fourths of its length from the inner end, that is, the end which comes in contact with the liquid in the bottle.

For still greater compressibility grooves, *c*, may be 60 formed by means of a drift, these grooves extending from the inner surface of the cylinder formed by the cork body, *a*, and the drilled hole, *b*, as shown in Fig. 4 or grooves, *c*, may be arranged outside the cork body as shown in Fig. 5. In other cases the exterior surfaces are 65 grooved circumferentially as shown in Fig. 7, the circumferential grooves, *c*, being preferably fine and closely set. The surface may be provided with one continuous groove or with separate grooves arranged in rings. 70

In cases where the inclosed fluid is of an effervescent nature, a disk of wood or thin metal, *e*, is employed which prevents the fluid escaping round the cork screw when such is inserted; it is also useful for making the stopper more difficult to eject. Further, when the 75 plug, *e*, is made of wood compressed or otherwise treated in accordance with this invention, on becoming soaked it exerts a radial pressure on the sides of the cork and this assists in making a fluid tight joint, and when made of metal it prevents the hollow cylindrical part 80 of the cork from being squeezed too much radially inwards. External grooves may be used as shown in Fig. 5 either with or without the plug, *e*.

A capsule, *d*, may be inserted on the end of the stopper in addition to the pitch or other water-proofing material or a covering of paper or the like may be provided to assist the water-proofing agent. The capsule, *d*, may be arranged on the inner end or the outer end or on both and may be formed of any suitable material such as metal, celluloid or vulcanite. The form of this 90 modification will be clearly seen from the sectional view, Fig. 3, which represents a stopper provided with a closing plug, *e*. The closing plug, however, may be dispensed with when the liquid contained in the bottle is not of an effervescent nature. Further, the form 95 shown in Fig. 3 may be inverted, in which case it is preferred to place a capsule over the end of the hole, and the plug, *e*, is then dispensed with.

It will be understood that according to my invention in all cases the wood is treated with paraffin wax or the like or provided with a capsule at least on its outer end. Capsules, when used, are made of a material which is not affected chemically by the inclosed fluid. 100

In Fig. 8 there is shown a method of preventing the end of the top capsule when such is used from being 105 burried when the cork is being inserted. This consists in making an oblique incision, *h*, in the outer surface all round the cork and embedding the end of the capsule in the recess thus formed. In this way when the cork is being inserted the end of the capsule is protected 110

from direct contact with the side of the bottle and indeed the overlapping wood at *h* presses against the capsule and helps to hold it in place.

When an inner capsule is used means may be provided for allowing the escape of air from the bottle while the stopper is being inserted. This means conveniently consists of one or more grooves, *f*, (Fig. 6) formed in the side of the cork and extending longitudinally up the side of the cork for say two thirds of the length and conveniently to the point where the upper and lower capsules meet. The material of which the capsule is made may in addition be cleared away at this point as shown so as to leave the wooden body of the cork exposed. When the cork is being inserted the air escapes through the groove, *f*, and when the cork is in position the contained liquid passes up the groove and at the head comes in contact with the wooden body. The wood thus becomes soaked and expands, causing the cork to fill into the neck of the bottle and make a fluid tight joint therewith if it did not do so originally.

The capsules on the lower part of the cork may be carried all the way down as shown in Fig. 6 and sealed over the bottom face of the cork or they may extend downwards only part of the way or they may extend to the bottom of the cork but not be sealed over the bottom face. In all cases the lower capsules are cemented in any suitable manner to the cork body.

In order to prevent the capsule adhering to the bottom of the neck a roughened, milled or corrugated surface on the lower capsule is preferably provided as shown in Fig. 6. Any suitable lubricant is applied to the outer surface of the lower capsule. This lubricant enters into all the little spaces formed by the milled surface and thus prevents the stopper or the capsule adhering to the bottle neck.

In all cases it is preferred to provide a small hole, *g*, as shown. This is for facilitating the insertion of a cork screw.

40 By compressing wood for stoppers in the manner herein described the hard cellular structure is broken laterally without seriously damaging the longitudinal tissue which is the principal drawback to chemical

treatment of wood hitherto employed for rendering it compressible. According to this invention the hard cellular structure is broken laterally so that on soaking the body part the liquid with which the wood is soaked may, by permeating through the body, cause the fibers to be forced apart, so that, on drying, the fibers remain apart but are no longer so firmly bound by the normal cellular structure.

Having now described my invention what I claim as new and desire to secure by Letters Patent is:—

1. A bottle stopper having a body part of crushed wood in which the lateral cellular structure has been broken down, and water-proofing means on one side of said body, substantially as described.

2. A bottle stopper having a body part of crushed wood in which the lateral cellular structure has been broken down, and water proofing means on the outside of said body, substantially as described.

3. A bottle stopper having a body part of crushed wood in which the lateral cellular structure has been broken down, and a capsule on one end of said body, substantially as described.

4. A bottle stopper having a body part of crushed wood in which the lateral cellular structure has been broken down, and a capsule on the outer end of said body, substantially as described.

5. A bottle stopper having a hollow part made of wood in which the lateral cellular structure has been broken down, and water-proofing means on said body part.

6. A bottle stopper having a hollow body part made of wood in which the lateral cellular structure has been broken down, a capsule on the outer part, and a capsule on the inner part, substantially as described.

7. A bottle stopper having in combination, a hollow body part made of crushed wood, a plug closing the inner end of said hollow body part, and a capsule over the outer end, substantially as described.

8. A bottle stopper having in combination, a hollow body part made of crushed wood, a plug closing the inner end of said hollow body part, and capsules over both ends.

9. A bottle stopper having a body part of crushed wood in which the lateral cellular structure has been broken down, and inner and outer capsules on said body, said inner capsule being milled and grooved on its surface, substantially as and for the purposes described.

In testimony whereof I affix my signature in presence of two witnesses.

GEORGE HOOKHAM.
